C. F. RANDALL

POCKETED CARRIER EQUIPMENT

Filed Feb. 15, 1918

UNITED STATES PATENT OFFICE.

CHARLES F. RANDALL, OF BOSTON, MASSACHUSETTS, ASSIGNOR, BY MESNE ASSIGNMENTS, TO MILLS BELT COMPANY, OF WORCESTER, MASSACHUSETTS, A CORPORATION OF MASSACHUSETTS.

POCKETED CARRIER EQUIPMENT.

Application filed February 15, 1918. Serial No. 217,407.

To all whom it may concern:

Be it known that I, CHARLES F. RANDALL, a citizen of the United States, residing at Boston, in the county of Suffolk, State of Massachusetts, have invented a certain new and useful Improvement in Pocketed Carrier Equipments, of which the following is a specification, reference being had therein to the accompanying drawings.

10 The invention is an improvement in pocketed carriers made of woven material of the class embracing cartridge-carriers, hospital corps belts, medical officers' belts, and various other carriers having special adaptations.

The invention relates to the pockets and pocket-covers or flaps of carriers of the general class just mentioned:

15 The invention is especially applicable for the production of body-supported carriers having smooth front pockets; that is to say, carriers forming part of military or the like equipment, worn by being supported upon the body of the wearer, and furnished with 20 one or more pockets having their cover or flap arrangements, and the fastening devices therefor, located at the top of the pockets so that the pocket-fronts are clear and smooth in the closed condition of the pockets. 25 However, the main feature of the invention is applicable also in the case of a pocket having a cover or flap-member that folds down against the pocket-front.

30 The invention consists, essentially, in a pocketed carrier having combined with the pocket thereof a pair of cover or flap-members located at the back and front of the pocket-mouth, respectively, which are adapted to fold in opposite directions toward 35 each other and interlap over the said mouth, giving double weather-protection, and constituted by prolongations of the back and front of an internal reinforce or lining for the pocket-back, pocket-front, and pocket-bottom.

The invention may be embodied variously in practice. The drawings show different embodiments of the features thereof.

40 Fig. 1 of the drawings is an isometric view of two of the smooth-front pockets of a cartridge-carrier containing one of the said embodiments.

Fig. 2 is a view of the open pocket of Fig.

1 in vertical cross-section on a somewhat larger scale. 55

Fig. 3 is a view showing in vertical cross-section an embodiment in which the rear cover or flap-member folds down against the pocket-front.

Fig. 4 is a view showing in vertical section a pocket having a rear cover or flap-member of single thickness that folds down against the pocket-front. 60

Fig. 5 is a view in vertical cross-section of a pocket having a strap combined with 65 cover or flap-members like those of Figs. 1 and 2, for holding them closed, instead of the fastener-arrangement of said figures.

Fig. 6 is a face view of the pocket shown in Fig. 5. 70

Referring to the drawings,—

The pockets 1, 1, may be woven integral with the body-supported supporting-band or backing 2, which is regarded as best in practice, or may be made separately in approved manner (either by weaving them as pockets or by stitching them into shape) and then attached to the said supporting-band or backing. Or, according to another known mode of construction, the carrier may be 75 composed of separately produced backing and facing webs, the latter woven with fullnesses to form pocket-pouches, fastened together face to face. A carrier may comprise either a single pocket or a series of pockets 80 woven upon or applied to a supporting-band or backing. 85

At 3 is the combination cover or flap and reinforce piece. This piece is composed of a suitable length of a selvage-edged webbing 90 of the proper width for the combined cover or flap-member and internal reinforce. It may be of uniform width throughout, or its width may be varied in divergent portions of its length by well-known procedure in weaving. The two prolongations thereof at the mouth of the pocket constitute the rear and front cover or flap-members aforesaid. In Figs. 1 and 2 the said members are marked 3^a and 3^b, respectively. In Fig. 3 they are 100 marked 3^c and 3^d, respectively; in Fig. 4 the respective cover or flap-members are marked 3^e and 3^f; and in Figs. 5 and 6 they are marked 3^g and 3^h. The said cover or flap-members are connected, respectively, with 105 the pocket-back 1^a, and the pocket-front 1^b,

and are adapted to be closed down together over the mouth of the pocket, in interlapping relation with each other as in the case of the closed pocket of Fig. 1. As shown 5 in Figs. 2, 3, 4, and 5 the main portion of the piece 3 extends down within the pocket and constitutes an internal reinforce or lining for the pocket-back, pocket-bottom, and pocket-front.

10 The connection of the cover or flap-members with the pocket-back and pocket-front is effected by means of lines of stitches 4, 4, or other suitable fastenings, engaging with the piece 3 at the top of the pocket.

15 In the case of the smooth-front construction shown in Figs. 1 and 2, the two cover or flap-members 3^a and 3^b are short, and in their closed condition are located wholly at the top of the pocket, leaving the pocket-front clear and smooth. The members 5 and 6 of the cover or flap fastening device are so applied to the said cover or flap-members 3^a, 3^b, as to engage with each other at the top of the pocket, thereby locating the fastening device also at the top of the closed pocket.

20 In the case of the construction shown in Fig. 3, the front cover or flap-member 3^a is short and similar to the front cover or flap-member 3^b of Figs. 1 and 2, but the rear cover or flap-member 3^c, is long enough to fold down in front of the pocket-front. Its free end is adapted to be fastened down in usual manner against the 25 pocket-front by the fastening device, the latter comprising, in this instance, interengaging members which are attached to the pocket-front and cover or flap-member 3^c, as usual.

30 The portions of material constituting the front and rear cover or flap-members of Figs. 1, 2, and 3, are shown as folded back upon themselves so as to produce smooth, firm, and finished ends upon the cover or flap-members. The cut ends of the turned-back portions are shown as entered and confined between the adjacent portions of the combination cover or flap and reinforce pieces and the pocket-walls, whereby such 35 cut ends are concealed and protected and fraying-out is provided against. They are secured in such confinement through being engaged by the stitches or other fastenings 4, 4.

40 The free end of the rear cover or flap-member 3^c of Fig. 3 may be made pointed, in practice, by tucking portions of the fold back in between the two thicknesses composing such cover or flap-member and securing the tucked-in portions in place by stitches. The side-margins of the two thicknesses 45 comprising the rear cover or flap-member 3^c of Fig. 3 and other two-thickness cover or flap-members may be fastened together by 65 lines of stitches.

In the case of the construction shown in Fig. 4, the front cover or flap-member 3^c is like the corresponding member of Figs. 1, 2, and 3, but the rear cover or flap-member 3^c is of single thickness, as in the case of the 70 covers or flaps of the construction heretofore usual, and is finished off at its free end in the usual manner, and said free end is fastened in place at the front of the pocket through the interengagement of the members of its 75 fastener.

The pockets of Figs. 3 and 4, present the same, or substantially the same, external construction and appearance as pocketed carriers such as are extensively in use at the 80 present time, but have increased weather-protection at the top, together with the applied internal reinforce or lining.

85 Figs. 5 and 6 show a construction which corresponds in the main with that shown in Figs. 1 and 2, but without fastener-members applied to the cover or flap-members as in Figs. 1 and 2. In Figs. 5 and 6 the interlapping cover or flap-members, which are marked 3^a, 3^b, are fastened down by a strip 9, of any approved width, attached by one end thereof to the rear of the pocket, as by having such end inserted between the pocket-back and the combined cover or flap and reinforce piece and caught by the 95 stitches 4 and additional stitches 4^a. The free end of this strip or tape is adapted to fold down at the front of the pocket-front, and to be fastened down as in the case of the cover or flap heretofore in common use, 100 namely, through the interengagement of the members of a fastener-device, one of such members being attached to the pocket-front and the other member, 6, to the strip or tape.

105 The specific construction of the interlapping cover or flap-members, and specific manner of finishing the same off, may be varied more or less in practice.

110 The invention renders it unnecessary to weave the pocket-back or supporting-web with a housing-slit for the reception of the attaching end of a cover or flap, or to weave the pocket-front or the cover or flap-members with such slits. It also renders it unnecessary to weave the pockets with integral 115 reinforcements. The process of weaving the pockets is simplified and expedited very appreciably by my invention, so that the cost of pocket carrier webs is reduced and the speed of production increased. By having 120 the pair of cover or flap-members constituted by integral portions of one piece of material I avoid having to attach separate pieces of material to the back and front respectively of a pocket. Consequently, the work 125 of connecting the pair of cover or flap-members is simplified and facilitated. Both of the cover or flap-members are more securely attached to a pocket than would be the case if either of them should consist of a small 130

piece of material, separately stitched to one of the pocket-walls. The one-piece inserted lining-piece forms a continuous smooth interior surfacing for the front-wall, pocket-bottom, and back-wall, without any internal projection or shoulder capable of obstructing the insertion or withdrawal of cartridges, etc. In the case of pockets in which a portion of a flap-piece is entered into a pocket and fastened in place within the pocket, the end of the inserted portion constitutes such a shoulder and obstruction, especially if such end be turned back upon itself to conceal a cut edge, and stitched through both thicknesses, as usual. If the end should not be turned back upon itself to conceal the cut edge, the latter would fray out in use, so that loose ends of yarns would be freed, and the end would eventually break loose from the securing stitches.

What is claimed as the invention is:—

1. A pocketed carrier of woven material comprising a body-supported band or backing, a pocket outstanding therefrom, and a one-piece inserted lining-piece forming a continuous interior surfacing for the front-wall, pocket-bottom, and back-wall, with one extremity thereof extending out of the pocket at the back thereof to constitute a back cover or flap member and the other extremity thereof extending out of the pocket at the front thereof to constitute a front cover or flap member.

2. A pocketed carrier of woven material comprising a body-supported band or backing and a plurality of pockets outstanding therefrom in exposed position, respectively

having combined therewith an internal reinforce or lining having prolongations thereof at both the front and the rear of the pocket-mouth constituting a pair of cover or flap-members, one thereof folding from the pocket-front rearwardly and the other from the pocket-rear forwardly, so that the two members interlap over said mouth, with the free ends of said prolongations doubled-back and fastened between the lining and the pocket-walls.

3. A pocketed carrier of woven material in which the usual cover-flap housing-slit is dispensed with comprising a body-supported band or backing and a plurality of pockets outstanding therefrom in exposed position, and having contained within each pocket an internal reinforce or lining having prolongations extending out of the pocket interior at both the front and rear of the pocket-mouth constituting a pair of cover or flap-members, one thereof folding from the pocket-front rearwardly leaving a smooth front and the other from the pocket-rear forwardly, so that the two cover or flap-members interlap over said mouth, and having fastening means for said prolongations of the internal reinforce or lining located entirely at the top of the pocket, whereby an improved carrier having smooth-front pockets is provided.

In testimony whereof I affix my signature in presence of two witnesses.

CHARLES F. RANDALL.
